F. H. BROWN,
MACHINE FOR WEAVING BASKETS.

No. 69,309.

Patented Oct. 1, 1867.

Franklin H Brown

United States Patent Office.

FRANKLIN H. BROWN, OF CHICAGO, ILLINOIS, ASSIGNOR TO HIMSELF,
E. F. PEUGEOT, AND LEMUEL H. FLERSHEIM, OF SAME PLACE.

Letters Patent No. 69,309, dated October 1, 1867.

IMPROVEMENT IN MACHINE FOR WEAVING BASKETS.

The Schedule referred to in these Letters Patent and making part of the same.

TO WHOM THIS MAY CONCERN:

Be it known that I, FRANKLIN H. BROWN, of Chicago, in the county of Cook, and State of Illinois, have invented a new and useful Machine for Forming and Weaving Baskets or similar kinds of work; and I do hereby declare that the following is a full and exact description thereof, reference being had to the accompanying drawings and letters of reference marked thereon, making a part of this specification, in which—

Figure 1 is a side view of my basket machine, showing a vertical section of the skeleton form and cylinder.

Figure 2 is a view of that part of the skeleton form which faces the cylinder; this figure also shows the weaving devices upon a standard which may be made to oscillate.

Figure 3 is a cross-section of the cylinder as seen from the direction of the skeleton form.

Figure 4 is a top view of my basket machine, with all of its parts, as seen when in operation.

Figure 5 is a front view of the jaw and packing device F, showing a cross-section of one of the forms, E, and the loose eye 9, thus showing their manner of construction and combination.

My invention relates to that class of machines which are constructed to perform certain kinds of work automatically, and is to be used more especially in making baskets of various forms; and its nature consists in forming a basket into any desired shape by means of a skeleton form or forms; also carrying the filling to its proper place by means of movable jaws and packing devices so arranged that as the filling is packed, the packing and forming device F, by means of rods connected with devices in the cylinder, and controlled by cam G and H, move a less distance equal to the width of the filling; also for attaching a weaving device or the parts for guiding the filling and actuating the uprights to an oscillating standard, for the purpose of weaving baskets of an irregular form.

Construction.

To enable others skilled in the art to make and use my invention, I will describe the method of construction and operation.

B represents the shaft which is attached to the frame A; K K' represent shoulders which are also attached to shaft B; Y represents the spokes which are attached to K' and held in position by set-screws; E represents the forms, which are made of spring brass or any other suitable material, and are attached to shou der K, as shown in fig. 1, being held into proper position by set-screws, and can be adjusted a greater or less distance from the shaft B in shoulder K, for the purpose of varying the size or form of the basket. The form of the basket may also be changed by using various shapes of forms E. The front ends of the forms E are connected to pieces L L'; these pieces are passed through the slots of spokes Y, and are made to move down, as shown by the dotted lines between the shaft B and forms E in fig. 1, as more fully explained hereafter. The guide pieces M are made sloping down to their centres, as shown in fig. 2, and are attached to the pieces L L', as shown in figs. 1 and 2, and are used for the purpose of guiding the uprights V into the jaws a a. T represents the teeth which form the controlling band, they being flexible, as shown in fig. 1 by dotted lines, and are held in position by the braces U. They are made flexible, so as to yield in case the device F or filling 8 should accidentally strike against them while in operation. The band X is attached to the spokes Y, and may be of any desired form to correspond with the shape of the basket, its use being to act as a resistant to the cam Z as it forces down the pieces L L', and also to control the position of the weaving device. N is a projection attached to pieces L L', as shown in fig. 4, its use being to press against the tail piece f as it is brought in contact with N, and thus open the jaws a a. The spring g acts against the inside of tail piece f, forcing the jaws a a together, thus clasping the uprights V. The packing and forming device F is attached to the forms E by means of the eye 9, which is made loose to enable the device F to retain its vertical position as it slides along the forms E. The rivet b is for the purpose of forming a joint for the jaws a a. O is a rod connecting the packing and forming device F with the rod Q and slide f, as shown in fig. 1. Piece P is made so as to be adjusted on rod Q by means of a set-screw, R, in order that it may be accommodated to the adjustment of forms E. The pieces f are made to slide in the openings 10 of the cylinder D, as clearly shown in fig. 4, by means of the cams G and H. The cams G and H and screw C are connected to a stationary sleeve passing around shaft B, and may be turned for the purpose of adjustment, and held in position by set-screws 12. The cam G is attached to the slide I,

which is dove-tailed to the slide I' , and is made to move back regularly to accommodate itself to the filling 8 by means of the screw C and its connection J . Screw C is made to revolve, being connected by gearing 88 with shaft B . Cam H is made stationary, and its use is to return the slides g and the packing device F to their original position. The original position of the packing and forming device F is to the front end of the form, and near the guide M . The holder 3 is made substantially as shown in figs. 2 and 4, and is attached to upper end of standard 4 , its use being to hold the weaving device and cam Z in position. The pieces L' , while passing under the cam Z , cause the jaws $a a$ to pass under and free from the filling which is passing through separator 2 while the uprights are allowed to pass over and are forced under the separator alternately by means of the wheel 6 . When the pieces L' have passed the cam Z , they spring back to their original position, thus enabling the guide pieces M , in connection with the jaws $a a$, to again control the uprights V . The standard 4 is pivoted at 5 so as to oscillate when the band X is of an irregular shape.

Operation.

The uprights V can be put on the forms E in the usual manner, care being taken that the uprights are placed into each tooth T and the guide pieces M , which will guide them into the jaws $a a$. The cam G is placed in position over the cylinder D , as shown in figs. 1, 3, and 4. The filling 8 is passed through the separator, and is drawn alternately over and under the uprights in a diagonal line, as shown in fig. 4. Then power is applied to the shaft B , revolving the forms E and cylinder D ; this brings the rods Q , connected with the slides g , against the cam G , forcing, by means of the rod O , the packing and filling device F forward from its original position. This causes the jaws $a a$ to close on the uprights V , thus pressing the filling 8 down to its proper place and allowing the uprights V to slide through the eye formed by the closed jaws $a a$, causing the uprights V to conform to the shapes of the forms E , as shown by the dotted lines above the uprights V in fig. 1, the uprights being retained to this form by the filling 8 as the work progresses. After the weaving is completed the basket may be removed from the machine. The connecting piece J is then raised to enable the cam G to be slid back to its original position, ready to weave another basket.

Having thus fully described my invention, what I claim, and desire to secure by Letters Patent of the United States, is—

1. A skeleton basket-form, as and for the purposes set forth.
2. The packing and forming device F or its equivalent, as and for the purposes specified.
3. The guide pieces M , constructed and operating as and for the purposes specified.
4. Cam Z , in combination with the band X , as and for the purposes specified.
5. The flexible teeth T of the controlling band, as and for the purposes set forth.
6. The holder 3 , in combination with rod 1 and cam Z , as and for the purposes set forth.
7. The cam G , in combination with the screw C , as shown, and for the purposes specified.
8. The slide g , in combination with the packing and forming device F , as and for the purposes set forth.
9. In a basket machine the oscillating standard 4 , in combination with the weaving device, as and for the purposes specified.
